UNITED STATES PATENT OFFICE.

VINNIE F. CREEGAN, OF LOS ANGELES, CALIFORNIA.

PORTABLE SOAP HOLDER.

Application filed June 21, 1926. Serial No. 117,458.

My invention relates to and has for its purpose the provision of an extremely simple, inexpensive and durable device by which a cake of soap can be securely held in the hand and the necessary manipulation as in washing greatly facilitated, all without the necessity of bringing the hand into actual contact with the soap.

It is also a purpose of my invention to provide a soap holder which is adjustable to receive and securely clamp soap cakes of various sizes in such manner that the possibility of the soap dropping from the holder is positively prevented, both during manipulation of the soap and when the soap is not in use, the holder providing means by which the soap can be suspended on a wall bracket to quickly drain and dry.

I will describe only one form of soap holder embodying my invention, and will then point out the novel features thereof in claims.

In the drawings—

Figure 1 is a view showing in bottom plan one form of soap holder embodying my invention;

Figure 2 is a view showing the soap holder in side elevation, and with a cake of soap in applied position thereto;

Figure 3 is a view showing the soap holder in top plan;

Figures 4 and 5 are transverse sectional views taken on the line 6—6 of Figure 2, showing respectively the normal position of the jaws and the position of the jaws when gripping a cake of soap.

Referring specifically to the drawings, in which similar reference characters refer to similar parts in each of the views, my invention in its present embodiment comprises a handle H constructed from a single length of relatively heavy wire which is bent upon itself substantially in the form of a U, with its free ends flattened, as indicated at 15, and riveted or otherwise secured to the upper side of a resilient member R. This member R is in the form of a leaf spring, and consists of a single sheet of resilient metal to the central portion of which is secured the ends 15 of the handle H in such manner as to allow of a limited flexing of the member in moving a pair of jaws J to contracted or expanded position.

The jaws J are in the form of stamped sheets of suitable metal riveted or otherwise secured to the marginal edges 16 of the resil-

ient member R, the latter being bent at an angle so that in the secured position with respect to the jaws the latter are normally held in converging relation as shown in Figure 4. These jaws J are constructed to provide at their side edges ribs 17 which function to reinforce the jaws as well as ornament the same. These ribs are extended to merge into a circular rib 18 on the ear extension 19 of the jaws. The two ears of the two jaws are adapted to be gripped in moving the jaws to expanded position, the annular ribs 18 forming sockets in the ears in which the fingers fit.

The longitudinal edges of the jaws J and J' are flanged and corrugated to provide inwardly extending teeth 20 adapted to penetrate a cake of soap and to thus firmly hold the cake between the jaws. To insert a cake of soap into the holder the ears 19 are gripped and forced toward each other, thereby flexing the member R sufficiently to move the jaws to an expanded position in which the two sets of teeth 20 are sufficiently spaced to allow the insertion of a cake of soap therebetween. Once the cake is inserted the jaws may be released, and under the action of the resilient member they are contracted to cause the teeth 20 to penetrate the cake of soap sufficiently to firmly grip and thus hold the cake between the jaws. The back edge of the cake, as shown in Figure 5, has contact with the inner side of the resilient member R, so that the latter serves to prevent any movement of the cake between the jaws.

With the cake in applied position to the holder, as shown in Figure 2, it will be manifest that by gripping the handle H one may manipulate the soap cake in any manner desired to apply soap to any articles to be washed or the manipulation of the soap in water for producing soap suds. In the manipulation of the soap holder the hand does not come in contact with the soap, and when the soap is not in use it can, through the medium of the holder, be suspended on the wall in a manner to hold the soap out of contact with the wall and to permit free drainage of water therefrom and thus cause the rapid drying of the soap. As the soap is consumed it can be moved in new positions within the holder by manipulation of the jaws, as will be understood, in order that the soap can occupy the best position for application to articles. The jaws are ad-

justable to receive and grip soap cakes of various siezs and to fixedly position the soap cake in the holder so that its manipulation will be facilitated.

5 Although I have only shown and described one form of portable soap holder embodying my invention, it is to be understood that various changes and modifications may be made therein without departing from the 10 spirit of the invention, and the scope and spirit of the appended claims.

I claim:

15 1. A soap holder comprising a handle constructed of a single length of material bent upon itself in the form of a **U** and having flat free ends, a leaf spring bowed and secured to the free ends of the handle, and a pair of jaws secured to those edges of the spring parallel with respect to the handle,

said jaws having toothed edges disposed at 20 one side of the spring and handle and operating ears disposed at the other side of the spring and handle by which the jaws can be moved from a contracted position to an expanded position.

2. A soap holder comprising a handle, a bowed leaf spring secured to the handle and having marginal edge portions disposed at an angle with respect to the body of the spring, and jaws secured to the marginal 30 edge portions of the spring so as to extend to opposite sides of the latter, one end of each jaw being inturned and serrated to provide teeth, and the other ends of the jaws being constructed to form countersunk ears 35 adapted to be gripped in manipulating the jaws.

VINNIE F. CREEGAN.
